MEANS FOR FEEDING DE-ICING LIQUIDS TO AIRFOIL SURFACES

Camille Clare Sprankling Le Clair,
Ealing, London, EnglandApplication November 2, 1942, Serial No. 464,186
In Great Britain June 28, 1941

12 Claims. (Cl. 244—134)

This invention relates to improvements in means for feeding de-icing liquids to airfoil surfaces, such as wings, tailplanes, ailerons, rudders, fins and so on, whereby the liquid is fed through channels provided in or on the part for distribution on the surface thereof.

In known means of the kind referred to difficulty is experienced in obtaining a uniform distribution of liquid owing to the resistance to flow in the channels provided causing a steep pressure gradient therein and it is one object of the present invention to avoid this difficulty.

Another object is to provide de-icing feeding means for airfoil surfaces in the form of channel elements which offer little resistance to the flow of liquid and, therefore, low pressure gradient in the longitudinal direction, but great resistance and, therefore, high pressure gradient in the lateral direction.

Another object is to provide a channel element for feeding de-icing liquids to airfoil surfaces which has uniform flow characteristics throughout its length so that the amount of liquid distributed per unit of channel length is approximately uniform.

Another object is to provide a novel construction for channel elements of the kind referred to wherein one or any number of capillary liquid feeding strips may be provided. In this specification a channel element having one capillary strip is referred to as a "single channel element" or "single element"; one having two capillary strips is referred to as a "double channel element" or a "double element"; and one having more than two capillary strips is referred to as a "multiple channel element" or a "multiple element."

Another object is to provide a novel channel element having a simple construction and wherein the thickness and spacing of the capillary strips define the size of the liquid or channel passage.

Another object is to provide a channel element having novel means for securing the parts thereof together.

Another object is to provide a novel channel element construction which permits great flexibility in the arrangement and placing of the capillary strips and the channel passages.

Another object is to provide a novel channel element of the kind referred to which has a minimum of parts and which is easy and inexpensive to construct.

Other objects and advantages will become apparent from the following description of preferred embodiments of the invention taken in conjunction with the accompanying drawing in which:

Fig. 1 is a perspective view showing one method of constructing a double channel element from two metal strips and two felt strips;

Fig. 2 is a sectional view of a double element, and shows additional means for preserving the spacing between the top and bottom metal strips;

Fig. 3 is a sectional view corresponding to Fig. 2, but shows an alternative method of preserving the spacing between the top and bottom metal strips;

Fig. 4 is a sectional view of a single element;

Figs. 5 and 6 are sectional views of multiple elements; and

Fig. 7 is a sectional view of an alternative form of the invention.

In the construction shown in Fig. 1, the double channel element comprises an upper strip 1 of metal and a lower strip 2 of metal, the strips being held in spaced relationship by means to be described hereinafter. Along each longitudinal marginal edge of the strip 1 there is provided a number of spaced projecting tongues 3, which are integral with the strip. Each longitudinal edge of the metal strip 2 is also formed with a number of spaced, projecting tongues 4 identical with the tongues 3 and integral with the strip. Although an alternative arrangement is shown in the drawing, it is preferred to arrange the tongues on one longitudinal edge of each metal strip between the tongues on the opposite longitudinal edge of the strip.

The channel element also comprises two felt strips 5 and 6. The top metal strip 1 is arranged on top of the felt strips 5 and 6 and the bottom strip 2 is arranged beneath them, and the inner longitudinal edges of the felt strips are overlapped by the strips 1 and 2 to the required extent so as to provide a rectangular channel passage for the liquid between the strips 1 and 2 and the inner longitudinal edges of the felt strips. In building up the assembly of the strips 1, 2, 5 and 6, the pointed ends of the tongues 3 and 4 are forced, respectively, downwards and upwards through the felt strips 5 and 6 as shown along the right hand longitudinal edges of the top and bottom strips 1 and 2 in Fig. 1. Thereafter, as shown along the left hand longitudinal edges of the metal strips 1 and 2 in Fig. 1, those parts of the tongues which protrude through the felt are bent over inwardly so that they bear upon the lower and upper surfaces, respectively, of the strips 2 and 1.

In Fig. 1 it will be seen that the tongues 3 are intended to be disposed substantially midway between the tongues 4. It has been found to be convenient to make the length of each tongue equal to about four times the thickness of the felt strips, and the gaps between the tongues may be from two to three times the width of the tongues at their bases.

In order to maintain the correct distance between the metal strips 1 and 2, the strip 1 may be formed with a number of longitudinally-

spaced, inwardly-projecting depressions or spacers 7. The bottom strip 2 may also be formed with a number of longitudinally spaced, inwardly-projecting depressions or spacers 8. The depth of the spacers 7 and 8 is substantially equal to the thickness of the felt strips 5 and 6. When the channel element is assembled, the spacers 8 are disposed substantially midway between the spacers 7. If so desired, the bases of the spacers 7 may be welded to the inner surface of the bottom strip 2 and the bases of the spacers 8 may be welded to the inner surface of the top strip 1.

An alternative means for maintaining the metal strips 1 and 2 at the correct distance apart is shown in Fig. 3. In this construction, the top metal strip 1 is formed with a number of inwardly-projecting spacers 9 and the metal strip 2 is formed with an equal number of inwardly-projecting spacers 10. The depth of the spacers 9 and 10 is substantially equal to half the thickness of the felt strips 5 and 6. When the channel element is assembled, the spacers 9 on the top strip 1 are substantially coaxial with the spacers 10 on the bottom strip 2 and the bases of each pair of adjacent spacers are in contact. If so desired, the contacting spacers may be welded together.

Fig. 4 shows a single channel element, which comprises a metal U-shaped member comprising a top strip 1 and a bottom strip 2 interconnected by a side wall 11. A single felt strip 5 is clamped between the strips 1 and 2 by means of tongues 3 on the top strip and tongues 4 on the bottom strip.

Fig. 5 shows a multiple channel element comprising three channel passages formed by three pairs of opposite top and bottom metal strips 1 and 2, 1A and 2A and 1B and 2B, and four felt strips 5, 6, 5A and 6A. It will be seen that the felt strip 5 and one longitudinal edge of the felt strip 6 are clamped between the strips 1 and 2 and that the opposite longitudinal edge of the felt strip 6 is clamped between the strips 1A and 2A. One longitudinal edge of the felt strip 5A is clamped between the metal strips 1A and 2A, the opposite longitudinal edge of this felt strip being clamped between the top and bottom metal strips 1B and 2B. One longitudinal edge of the felt strip 6A is also clamped between the metal strips 1B and 2B.

The multiple channel element shown in Fig. 6 is similar to that shown in Fig. 5, but, as will be seen, the left hand longitudinal edge of the left hand felt strip 5 and the right hand edge of the right hand felt strip 5A are each clamped between a metal member such as shown in Fig. 4 comprising opposite top and bottom strips 1 and 2 interconnected by a side wall 11. As in the previously described construction, the metal strips 1, 1A, 1B and 1, and 2, 2A, 2B and 2 are provided with clamping tongues such as 3 and 4.

It will be understood that the multiple channel elements may comprise two or more channel passages.

The multiple channel element shown in Fig. 5 may be modified by adding a single channel element at the right hand edge of the multiple element. The construction can be visualized by assuming that the right hand edge of the right hand felt strip 6A in Fig. 5 is clamped between a metal member comprising top and bottom strips 1 and 2 and a side wall 11 as shown, for example, at the right hand edge of the right hand felt strip 5A in Fig. 6.

Further, the separate top or bottom metal strips 1, 1A, 1B or 2, 2A, 2B and the top or bottom

of the said metal member may be replaced by a continuous or single metal strip, for example, equal in width to the distance from the left hand edge of the left hand metal strip 1 or 2, as the case may be, to beyond the side wall 11 of the said metal member at the opposite edge of the multiple element. In this case, however, the said metal member need only have a top or a bottom strip 1 or 2 integral with a side wall 11. A construction of this character including a continuous bottom strip 12 is illustrated in Fig. 7, to which reference is now had. The edges of the separate top strips 1, 1A and 1B are again provided with tongues such as 3 which, after having been forced through the felt, are passed through slots formed in the said continuous or single metal strip 12 and then bent over in order to clamp the felt between the latter and said strips. The free edge of the top strip 1 of the said metal member at the right hand edge of the multiple element is provided with tongues 3 arranged to pass through the adjacent felt strip and through slots in the said continuous or single metal strip 12 before being turned over against the outer surface of the latter. The side wall 11 is also provided with clamping tongues 13 which are passed through slots in the last mentioned strip before being turned over against the said outer surface.

The length and width of the channel assembly is sufficient to cover or to form that part of the airfoil to which the de-icing liquid is distributed.

At one end of a channel element or of an assembly of elements the channel passage or passages are connected to a manifold or manifolds into which the de-icing liquid is pumped when required, the opposite ends of the channel passages being closed.

In the constructions described above, the channel elements have a uniform thickness and the metal strips are provided with smooth inner surfaces which will offer a minimum resistance to the small flow of liquid which is usually required. The liquid is intended to be distributed by capillary action through the felt.

If preferred the channel passages and/or the felt strips may be of tapering form to suit the tapering form sometimes used for airfoils. Any suitable capillary material such as unglazed ceramic, woven asbestos or glass fibre or bundles of inorganic fibres may, of course, be substituted for the felt referred to in the constructions above described. It is not essential to use metal strips provided the surfaces of the alternative material used are smooth and possess sufficient rigidity. If preferred, the strips of metal or alternative material may be attached to the felt by staples or the like.

I claim:

1. Means for feeding de-icing liquids to the surfaces of parts of aircraft such as airfoils and the like, including in combination, superimposed walls of material impervious to liquids, two strips of capillary material, part of one of said capillary strips adjacent to one of its longitudinal edges being positioned between said superimposed liquid impervious walls on one edge of said walls, and part of the other of said capillary strips adjacent to one of its longitudinal edges being positioned between said superimposed walls on the other edge of said walls, the facing longitudinal edges of said capillary strips being spaced apart so that a passageway is formed between said walls and said strips, and means integral with said liquid impervious walls for clamping said walls to said capillary strips.

2. The combination set forth in claim 1, in which said clamping means comprises a plurality of spaced apart tongues integral with said walls, said tongues being bent inwardly and passed through said capillary strips, and a portion of said tongues protruding from said capillary strips being turned inwardly across the wall on the opposite side.

3. Means for feeding de-icing liquids to the surfaces of parts of aircraft such as airfoils and the like, comprising a multiple channel element including in combination a plurality of spaced apart capillary strips, a pair of metallic walls connecting adjacent capillary strips, so that there is an arrangement of alternating capillary strips and metallic walls across the multiple channel element, said strips maintaining said walls in spaced relationship, said capillary strips and said walls forming a plurality of passageways therebetween, and means integral with said metallic walls and passing through said capillary strips for securing said walls and said strips together.

4. Means for feeding de-icing liquids to the surfaces of parts of aircraft such as airfoils and the like, comprising a multiple channel element including in combination, a plurality of spaced apart capillary strips, a continuous wall of liquid impervious material adapted to overlie all of said capillary strips and the spaces therebetween on one side thereof, a plurality of liquid impervious walls disposed on the side of said capillary strips opposite said continuous wall, said plurality of walls being equal in number to the number of spaces between said strips and bridging those spaces, and means integral with said walls for clamping said capillary strips between said continuous wall and said plurality of walls.

5. The combination set forth in claim 4, in which said continuous wall extends beyond the longitudinal edge of at least one end capillary strip, a liquid impervious wall disposed on the side opposite said continuous wall and coextensive with the extension thereof, and an end wall connecting said continuous wall and said second-mentioned wall to form a passageway adjoining said capillary strip.

6. Means for feeding de-icing liquids to the surfaces of parts of aircraft such as airfoils and the like, comprising at least one channel element including in combination a strip of capillary material, two spaced superimposed longitudinal metallic walls, one longitudinal edge of said capillary strip being positioned between said longitudinal walls, a side wall connecting said longitudinal walls opposite said capillary strip and spaced therefrom to form a passageway therebetween, and means integral with said longitudinal walls and passing through said capillary strip for clamping said longitudinal walls to said capillary strip.

7. The combination set forth in claim 6, in which said clamping means comprises a plurality of tongues disposed along the edges of said longitudinal walls, each of said tongues being inserted through said capillary strip and having its protruding tip turn over, across and into contact with the outer surface of the metallic wall on the other side of said capillary strip.

8. Means for feeding de-icing liquids to the surfaces of parts of aircraft such as airfoils and the like, comprising at least one channel element including in combination at least two spaced walls of liquid impervious material, at least two other walls formed by spaced strips of cap-

illary material clamped between said spaced walls, and means for maintaining said liquid impervious walls in spaced relationship, said spacing means comprising a plurality of spacer elements associated with each liquid impervious wall, said spacer elements having a depth substantially equal to the thickness of said capillary strips, the spacer elements on each of said walls projecting inwardly toward the opposite wall and each spacer element from one wall being adjacent a spacer element from the other wall, so that spacer elements from one wall are arranged alternately with the spacer elements from the opposite wall.

15. 9. A channel element comprising a generally U-shaped member formed by bending a metal strip so that it comprises two longitudinal walls integral with a side wall, a strip of capillary material disposed between said longitudinal walls with its inner edge spaced from said side wall, and means for clamping said capillary strip between said longitudinal walls comprising a plurality of spaced tongues along each longitudinal edge of said spaced walls, each of said tongues being inserted through said strip of capillary material and having its protruding tip turned over, across and into contact with the outer surface of the other spaced wall.

10. Means for feeding de-icing liquids to the surfaces of parts of aircraft such as airfoils and the like comprising at least one channel element including in combination a metallic channel-shaped member, a strip of capillary material disposed between the longitudinal edges of the gap at one side of said channel-shaped member and having the major body portion thereof projecting exteriorly beyond said channel-shaped member, said strip being spaced from the closed side of said channel-shaped member to form a passageway therebetween, and means integral with said channel-shaped member and passing through said capillary strip to secure said channel-shaped member and said strip together.

11. Means for feeding de-icing liquids to the surfaces of parts of aircraft such as airfoils and the like, comprising at least one channel element, including in combination, a strip of capillary material, two spaced apart superimposed longitudinal, rigid liquid impervious walls, one longitudinal edge of said capillary strip being positioned between said longitudinal walls, a side wall connecting said longitudinal walls opposite said capillary strip and spaced from said strip to form a passage therebetween, and means including structure integral with at least one of said walls and passing through said capillary strip for clamping said longitudinal walls to said strip.

12. Means for feeding de-icing liquids to the surfaces of parts of aircraft such as airfoils and the like, comprising a multi-channel element, including in combination, a plurality of spaced apart capillary strips, a continuous wall of liquid impervious metal adapted to overlie all of said capillary strips and the spaces therebetween on one side thereof, a plurality of liquid impervious metal walls disposed on the side of said capillary strips opposite said continuous wall, said plurality of walls being equal in number to the number of spaces between said capillary strips and bridging those spaces, and means integral with certain of said walls for securing said walls and capillary strips in assembled relation.

CAMILLE CLARE SPRANKLING LE CLAIR.
